(75) Inventor: Jamie Craig McCurrach, Amersfoort (NL)

* cited by examiner

(73) Assignee: Koninklijke Philips Electronics N.V., Eindhoven (NL)

Primary Examiner—Jennifer Rivard
(74) Attorney, Agent, or Firm—Ernestine C. Bartlett

() Term: 14 Years

(57) CLAIM

The ornamental design for a combined electric epilator device with ice-pack, as shown.

DESCRIPTION

Jul. 30, 2002 (WO) DMA/005 794

FIG. 1 is a perspective view showing my design;

(51) LOC (7) Cl. 28-03

FIG. 2 is a front elevational view thereof;

(52) U.S. Cl. D28/44.1

FIG. 3 is a rear elevational view thereof;

(58) Field of Search D28/44, 44.1,

D28/45-54; 30/526, 34.05, 34.1, 34.2, 41.9,

43, 43.1, 43.2, 43.3, 43.91, 43.92, 48-50,
85

FIG. 4 is a left side elevational view thereof;

(56) References Cited

FIG. 5 is a right side elevational view thereof;

FIG. 6 is a top plan view thereof; and,

FIG. 7 is a bottom plan view thereof.
